DRAWER SLIDE

Alfred F. Waller, St. Charles, Ill., assignor to
St. Charles Manufacturing Co., St. Charles, Ill.,
a corporation of Illinois

Application March 2, 1942, Serial No. 432,999

4 Claims.

(Cl. 308—6)

This invention relates to drawer slides and is more particularly concerned with an easy action roller bearing type drawer slide.

A salient feature of the drawer slide of my invention consists in the provision of three roller bearings, one at the front end of the guide and the other two in vertically spaced relation at the rear end of the slide, the front roller having rolling contact on the top thereof with a track surface on the slide, and the other two rollers being arranged for rolling contact on track surfaces on the top and bottom of the guide, so that there are two rollers providing rolling contact at all times regardless of the tilting of the drawer.

The drawer slide of my invention has the guide thereof formed from a single piece of sheet metal to channel-shaped cross-section for the desired lightness and strength, the roller mounted on the front end thereof being supported on the web of the channel and projecting through an opening in the upper flange, and the main body portion of the slide being also formed from a single piece of sheet metal to a generally channel-shaped cross-section for lightness and strength, the upper flange of the channel slide having rolling contact on top of the aforesaid roller on the guide, the channel of the guide fitting freely in the channel of the slide, and the two other rollers for the drawer slide being mounted on the rear end of the slide in vertically spaced relation for rolling contact on the outer side of the flanges of the guide.

The invention is illustrated in the accompanying drawing, in which—

Figure 1 is a perspective view of one of a pair of drawer slides made in accordance with this invention, the slide having an intermediate portion thereof broken away so as to permit showing it on a larger scale;

Fig. 2 is a full length side view of the slide on a smaller scale, and

Figs. 3 and 4 are vertical sections on the lines 3—3 and 4—4 of Fig. 2, looking in the direction of the arrows.

The same reference numerals are applied to corresponding parts throughout these views.

The reference numeral 5 in Fig. 3 designates a portion of a drawer adapted to be supported at opposite sides by drawer slide structures, like that indicated at 6, within a sheet metal or other cabinet. The drawer slide structure 6, it will soon appear, is for the right hand side of the drawer as viewed from the front. The left hand drawer slide structure is of course the counterpart of that shown. In other words, each of the two drawer slide structures comprises a stationary guide rail 7 adapted to be suitably secured to the side of the cabinet, and a movable

slide rail 8 adapted to be suitably secured to the drawer.

The guide rail is made from a single piece of sheet metal bent to channel-shaped section, so as to provide a vertical web portion 9 and upper and lower horizontal flanges 10 and 11. The front end of the web 9 is bent at right angles to close the front end of the channel, as indicated at 12, and there are attaching ears 13 bent from the edge portions of the flanges 10 and 11 at the front and rear ends of the rail for fastening the same to the inner side wall of the cabinet. A roller 14 of an anti-friction type is mounted on the inner side of the web 9 so as to project slightly through a hole 15 provided in the upper flange 10 near the front end of the guide rail, the bearing 14 being permanently secured to the web 9 by riveting, as indicated at 16 in Fig. 3. The slide rail 8 has the main body portion thereof made from a single piece of sheet metal bent to generally channel-shaped cross-section, so as to provide the vertical web 17 and upper and lower flanges 18 and 19. The flanges are bent to generally V-shaped section, as indicated at 20, and the free edge portions 21 are bent into the vertical plane of the web portion 17. A plate 22 has the edge portions 21 of the slide rail 8 welded thereto, as indicated at 23, and this plate has two anti-friction rollers 24 and 25 mounted thereon adjacent the rear end of the slide rail, the roller 24 being disposed above the guide rail 7 for rolling contact on top of the flange 10 and the roller 25 being disposed under the guide rail 7 for rolling contact on the bottom of the flange 11. The rollers 24 and 25 are both riveted to the plate 22, as indicated at 26 in Fig. 4. The roller 14, previously mentioned, has rolling contact with the body of the flange 18, as clearly appears in Fig. 3.

In operation, the present drawer slide structure always provides anti-friction roller support for the drawer at two points. That is to say, in the initial outward movement of the drawer, the rollers 14 and 24 provide the support and continue to do so until the drawer is pulled out more than half way, at which time, due to the tilting of the drawer on the front roller 14 as a fulcrum, the roller 25 is brought into play and contacts the bottom flange 11 of the guide rail. From that point on until the drawer is pulled all of the way out, the rollers 14 and 25 assume the load. In drawers having only one or two roller bearings in each drawer slide structure, the loaded drawer may operate fairly smoothly up to the point where the drawer is about half way out, then the front end of the drawer drops enough to make the rear roller bearing, if any, ineffective and there is accordingly too much loading on the front roller and it usually requires a heavy pull to overcome the drag in pulling the drawer the rest of

the way out. In pushing the drawer back in, where the drawer slide structure has only one or two roller bearings, there is the same objection, resistance being encountered at the rear of the drawer until the drawer has been moved in about half way to make the rear bearing effective. Drawers having only a single roller bearing in each drawer slide structure are, of course, much harder to operate for obvious reasons. The drawer slide of my invention avoids the objections just mentioned, because of the fact that each drawer slide structure has two rollers furnishing roller support in any position of the drawer. The lower rollers 25 are located close enough to the bottom of the guide rails 1 so that when they come into play it is not at all noticeable and the drawer is movable smoothly from one limit position to the other in either direction. The sheet metal construction and channel shape of both the slide and guide rails makes for lightness and strength as well as low cost of manufacture.

It is believed the foregoing description conveys a good understanding of the objects and advantages of my invention. The appended claims have been drawn to cover all legitimate modifications and adaptations.

I claim:

1. A drawer slide structure comprising, in combination, a stationary guide rail formed to channel-shaped cross-section to provide upper and lower track surfaces on the outer sides of its upper and lower longitudinal flanges, a relatively movable slide rail formed to channel-shaped cross-section and disposed in telescoping relation with the guide rail, and three roller bearings for anti-friction roller support of the slide rail on the guide rail, one mounted in the front end of the guide rail with the top portion thereof projecting slightly above the plane of the upper track surface through an opening provided in the upper flange of the guide rail, the slide rail having a track surface provided on the bottom of the upper flange thereof for rolling contact on the last mentioned roller, the two other roller bearings being mounted in vertically spaced relation on the rear end of the slide rail for rolling contact on the first mentioned track surfaces on the guide rail, the last mentioned roller bearings being spaced vertically a distance slightly greater than the distance between the upper and lower track surfaces on the guide rail to permit movement of the two roller bearings past the front roller in the removal and replacement of a drawer on which the movable slide rail is attached.

2. A drawer slide structure comprising, in combination, a stationary guide rail formed to channel-shaped cross-section to provide upper and lower track surfaces on the outer sides of its upper and lower longitudinal flanges, a relatively movable slide rail formed to channel-shaped cross-section and disposed in telescoping relation with the guide rail, and three bearing members for support of the slide rail on the guide rail, one mounted in the front end of the guide rail with the top portion thereof projecting slightly above the plane of the upper track surface through an opening provided in the upper flange of the guide rail, the slide rail having a track surface provided on the bottom of the upper flange thereof for bearing con-

tact on the last mentioned bearing member, the two other bearing members being mounted in vertically spaced relation on the rear end of the slide rail for bearing contact on the first mentioned track surfaces on the guide rail, the last mentioned bearing members being spaced vertically a distance slightly greater than the distance between the upper and lower track surfaces on the guide rail to permit movement of the two bearing members past the front bearing member in the removal and replacement of a drawer on which the movable slide rail is attached.

3. A drawer slide structure comprising, in combination, a one-piece, sheet metal, stationary guide rail formed to channel-shaped cross-section to provide upper and lower track surfaces on the outer sides of its upper and lower longitudinal flanges, the edge portions of said upper and lower flanges being bent to provide attaching ears in a vertical plane substantially parallel to the plane of the web portion of said guide rail and the upper flange of the guide rail having an opening provided therein at the front end thereof, a roller mounted on the web portion of the guide rail having its upper portion projecting slightly above the plane of the upper track surface through said opening, a relatively movable, one-piece, sheet metal slide rail formed to channel-shaped cross-section and disposed in telescoping relation with the guide rail, the upper flange of the slide rail providing a track surface on the bottom thereof engaging the top portion of the aforesaid roller, the upper and lower flanges of the slide rail being bent to substantially V-shaped cross-section and having the longitudinal edge portions thereof bent into a vertical plane substantially parallel to the web portion of the slide rail to form attaching portions, a plate secured to said attaching portions at the rear end of the slide rail, and two rollers mounted in vertically spaced relation on said plate for rolling contact on the first mentioned track surfaces on the guide rail, the last mentioned rollers being spaced vertically a distance slightly greater than the distance between the upper and lower track surfaces on the guide rail to permit movement of the two rollers past the front roller in the removal and replacement of a drawer on which the movable slide rail is attached.

4. A drawer slide structure, comprising, in combination, a stationary guide rail providing upper and lower longitudinal track surfaces thereon, a roller mounted on the front end portion of said guide rail and projecting slightly above the plane of the upper track surface, a relatively movable slide rail providing a track surface thereon overlying the top portion of the guide rail and engaging the aforesaid roller for support, and two rollers supported in vertically spaced relation on the rear end of the slide rail and having rolling contact on the first mentioned track surfaces on the guide rail, the last mentioned rollers being spaced vertically a distance slightly greater than the distance between the upper and lower track surfaces on the guide rail to permit movement of the two rollers past the front roller in the removal and replacement of a drawer on which the movable slide rail is attached.

ALFRED F. WALLER.
